WINDOW LOCK

Vincenzo Mecca, New York, N. Y.

Application January 30, 1935, Serial No. 4,002

5 Claims. (Cl. 292—195)

This invention relates to improvements in window locks in which provision is made for securely locking the two sashes of said window together in closed as well as partially opened positions.

An object of the invention is to provide a simple cheap lock which may be easily applied to the window. Another object resides in the provision of positive means, in a lock of the above character, for drawing the two sashes tightly together as well as holding them firmly under vertical pressure in a closed position. Further objects of the invention are hereinafter set forth.

Heretofore window locks have been manufactured in which a bolt has been employed that is adapted to be actuated in a vertical plane to a locking position. Such devices are incapable of locking the sashes in other than closed position, nor are they effective to hold the sashes under tension vertically to prevent rattling. Other forms of window locks include springs and cam surfaces, which latter have frictional engagement rendering the lock more difficult to operate.

My improved lock is designed to effectively close easily, and following which it may be as easily tightened. But even although it should not be fully tightened it still cannot be opened from the outside of the window.

My invention is fully set forth in detail in the following specification and drawing forming a part thereof in which latter I have illustrated a preferred embodiment of my invention.

Referring to such drawing,

Figure 1 is an inside elevation of a portion of the two closed sashes of a window with my improved lock shown applied thereto in locked position.

Figure 2 is a vertical section through the sashes taken on the line 2—2 of Figure 1, with the lock in elevation, and,

Figure 3 is a perspective view of the lock with the two cooperating parts in relative positions but abnormally separated to better illustrate details otherwise hidden.

In Figure 2 portions of an upper sash 10 and a lower sash 11 are shown with both in closed position. Each is provided with the usual cross frames 12 and 13 respectively, the tops of which are commonly in substantially the same plane when the sashes are closed, but with the said frames usually somewhat separated transversely from each other.

Upon the top of frame 12 of sash 10 a bracket 14 is secured as by screws 15. Bracket 14 has a

base 16 suitably apertured to receive screws 15, and another portion 17 extending upwardly perpendicular to base 16. Portion 17 is reinforced by a column 18, and is provided with a slot 19 extending transversely from one edge to beyond the vertical center line of the piece. This slot also extends rearwardly and bisects the column 18, so as to provide a lug 18a at the top of said column. The lower surface of slot 19 is preferably inclined downwardly from the horizontal toward its open end as at 19a.

A bolt 20 is adapted to extend through slot 19 with its rear end below lug 18a and above the top surface of the lower part of column 18. The upper portion of the latter and the lug 18a are drilled to loosely receive a pin 21 having a drive fit through bolt 20. Sufficient clearance is provided so that the pin and bolt are free to move together to a limited extent in a vertical plane. The bolt may thus be swung about the pin 21 through and out of slot 19.

The other end of bolt 20 is threaded to receive a wing nut 22.

Another angle bracket or fitment 23 is provided with an upright portion 24 and a base 25, the latter being apertured to receive screws 26 by which the bracket may be secured to the top of frame 13 of the lower sash 11.

The bracket 23 may be reinforced by rib 27, and the part 24 may be provided with a slot, or a plurality of slots, two in this instance, 28 and 29. The lower surface 28a of slot 28 is also preferably slightly inclined similar to slot 19, as shown in Figure 1.

With the brackets mounted as shown in Figure 1, with the top surfaces of frames 12 and 13 in substantially the same plane, the slot 28 will be slightly higher than slot 19. If the frames are not in a position corresponding to the above when the sashes are closed, then either bracket may be adjusted by the use of shims of paper or other suitable material so that the aforesaid slots will be offset with respect to each other, as above described, for the effective operation of bolt 20.

When the sashes 10 and 11 are closed with brackets 14 and 23 in the relative position shown in Figures 1 and 2, the bolt 20 may be rotated about pin 21 after first unscrewing the wing nut 22 sufficiently to allow the bolt to swing through and out of engagement with the slots 19 and 28, to thus unlock the window and permit the sashes to be opened without interference with the bolt. When the bolt is clear of both slots it will be supported on the top of column 18. 45 50 55

To lock the sashes in a closed position the bolt is swung in an opposite direction from the above, and since the pin 21 is loosely mounted within column 18, and because of the aforesaid clearance, the bolt 20 together with pin 21 will be free to move upwardly and permit the bolt to ride up the inclined surface 28a of slot 28, and when further rotated will press against the upper surface of slot 19, the said surfaces of the two slots 10 tending to wedge the sashes firmly closed. The nut 22 may then be tightened to draw the sashes together. These combined operations will effectively eliminate any tendency of the sashes to rattle.

15 If it is desired to lock the sashes in a partially open position slots 19 and 29 may be brought into registration by moving the upper sash down or raising the lower one. The bolt may then be applied to lock them together. They may then 20 be raised or lowered together to an extent limited by the distance between slots 28 and 29.

Various modifications within the scope of the appended claims may be made without departing from the spirit of my invention.

25 I claim:

1. A window lock comprising a bolt adapted to swing in a plane substantially normal to the sash movement, a support to which said bolt is pivoted, a fitment adapted to be secured to the sash which 30 is movable with respect to said support, said fitment having a slightly inclined surface along which said bolt is swung in moving about its pivot into locked position, whereby said sash is tightly closed by said bolt in moving to its closed position, said bolt having at least a limited movement 35 in a plane normal to the plane of its swinging movement, and an abutment surface substantially co-extensive with said inclined surface, secured to said bolt support close to said inclined surface and 40 adapted to engage the opposite side of said bolt from said inclined surface for transmitting the thrust of tightly closing said sash, whereby the stress on said bolt during its movement along said inclined surface in tightly closing said sash may 45 be principally that of shear and without any substantial flexure to said bolt support.

2. A window lock comprising a bolt adapted to swing in a plane substantially normal to the sash movement, a support to which said bolt is pivoted, 50 a fitment adapted to be secured to the sash which is movable with respect to said support, said fitment having a slightly inclined surface along which said bolt is swung in moving about its pivot into locked position, whereby said sash is tightly 55 closed by said bolt in moving to its closed position, and an abutment surface substantially co-extensive with said inclined surface, secured to said bolt support close to said inclined surface and adapted to engage the opposite side of said bolt from said inclined surface for transmitting the 60 thrust of tightly closing said sash.

3. A window lock comprising a bolt adapted to swing in a plane substantially normal to the sash movement, a support to which said bolt is pivoted, 65 a fitment adapted to be secured to the sash which is movable with respect to said support, said fit-

ment having a slightly inclined surface along which said bolt is swung in moving about its pivot into locked position, whereby said sash is tightly closed by said bolt in moving to its closed position, and an abutment surface substantially co-extensive 5 with said inclined surface, secured to said bolt support close to said inclined surface and adapted to engage the opposite side of said bolt from said inclined surface for transmitting the thrust of tightly closing said sash, and another 10 bolt guide surface opposite said abutment on said bolt support, with which said bolt may cooperate in swinging into a closed position, said fitment having a bolt receiving slot between its inclined surface and the sash to which it is attached, 15 whereby said sash may be locked in a partially opened position.

4. A window lock comprising a bolt adapted to swing in a plane substantially normal to the sash movement, a support to which said bolt is pivoted, 20 a fitment adapted to be secured to the sash which is movable with respect to said support, said fitment having a slightly inclined surface along which said bolt is swung in moving about its pivot into locked position, whereby said sash is tightly 25 closed by said bolt in moving to its closed position, and an abutment surface substantially co-extensive with said inclined surface, secured to said bolt support close to said inclined surface and adapted to engage the opposite side of said 30 bolt from said inclined surface for transmitting the thrust of tightly closing said sash, and another bolt guide surface opposite said abutment on said bolt support, with which said bolt may 35 cooperate in swinging into a closed position, said fitment having a bolt receiving slot between its inclined surface and the sash to which it is attached, 40 whereby said sash may be locked in a partially opened position, said bolt guide surface opposite said abutment being inclined at about the angle of the inclined surface on said fitment.

5. A window lock comprising a bolt adapted to swing in a plane substantially normal to the sash movement, a support to which said bolt is pivoted, 45 a fitment adapted to be secured to the sash which is movable with respect to said support, said fitment having a slightly inclined surface along which said bolt is swung in moving about its pivot into locked position, whereby said sash is tightly 50 closed by said bolt in moving to its closed position, said bolt having at least a limited movement in a plane normal to the plane of its swinging movement, and an abutment surface substantially 55 co-extensive with said inclined surface, secured to said bolt support close to said inclined surface and adapted to engage the opposite side of said bolt from said inclined surface for transmitting the thrust of tightly closing said sash, whereby the stress on said bolt during its movement along said inclined surface in tightly closing 60 said sash may be principally that of shear and without any substantial flexure, and a wing nut on said bolt adapted to engage a side of said fitment and clamp said sash against rattling with 65 respect to the bolt support.

VINCENZO MECCA.
